BASEBALL MASK

Hugo Goldsmith, Cincinnati, Ohio, assignor to
Sport Products, Inc., Cincinnati, Ohio, a corpora-
tion

Application August 8, 1950, Serial No. 178,233

1 Claim. (Cl. 2-9)

1

This invention relates to baseball masks of the type conventionally used by catchers and umpires and is particularly concerned with a mask of the bar type embodying certain improvements which increase the comfort to the wearer and the degree of protection accorded, but which at the same time render the mask less obtrusive and cumbersome without in any way affecting its utility.

Baseball masks generally are of two different types, the mesh type formed of interlaced wires, in most instances secured at the intersections by welding or the like, and the bar type in which the entire metal portion of the mask is formed from a single integral plate of lightweight metal, such as magnesium, Duralumin or the like. Bar type masks have to a large extent displaced the mesh type, particularly in professional use because they are, generally speaking, lighter in weight and provide a much better degree of visibility.

However, there have been in the past certain objections to masks generally, and particularly to those of the bar type. The present invention is concerned with the problem of correcting these various objections and providing a mask which is substantially more comfortable and which provides a greater degree of protection than any of the structures which have heretofore been in common use.

With this purpose in mind, one of the objects of the present invention has been to provide a mask of the bar type in which an upwardly extending projection eliminates any possibility of the user being hit on the top of the head by a ball. While this general arrangement has been suggested in the past, it has always been in connection with masks which were not firmly anchored to the wearer's head and which could and sometimes did slip down to a point where a ball could pass over the top of the mask and hit the head of the wearer. Because of the anchoring means provided by the harness utilized in the present invention, the head protecting extension is always maintained in a position above the wearer's head so that contact with the ball is virtually impossible.

Another object of the present invention has been to provide a minimum of padding positioned in selected areas only with an aperture of substantial width along the line established by the eyes and ears of the wearer. There are two purposes in this type of construction, the first being to increase the degree of side visibility through the mask, and the second, to pro-

2

vide ventilation to the wearer's face. This lack of ventilation is a particular problem in a bar type mask because of the comparatively large and enclosed areas provided, and is a source of considerable discomfort to a mask wearer who is sometimes required to keep the mask positioned continuously for a period of one-half to three-fourths of an hour on a hot day.

Another object has been to provide means for 10 adjustably positioning the mask on the head of the wearer. Since human heads differ very substantially in size and contours, the ordinary strap and buckle arrangement is frequently not sufficient to provide a really proper type of fit. In the 15 preferred embodiment of the present invention, a further degree of adjustability is provided in that the strap may be passed through either one of two or more longitudinally disposed apertures in the side of the mask plate, thereby greatly increasing the degree of adjustability.

Other and further objects and advantages will be apparent from the further and more detailed description of the invention when considered in conjunction with the drawings, in which:

25 Figure 1 is a side view of a mask representing a preferred embodiment of the invention positioned on the face of a wearer.

Figure 2 is a front view of the same mask.

Figure 3 is a rear view of the same mask, particularly illustrating the location of the padding with respect to the mask frame.

Referring now to the drawings for a further and more detailed description of the invention, the mask, which in its entirety is designated generally as 10, comprises the plate 11 which is 35 preferably cast from some lightweight metal of the types previously specified. The plate is generally oval in contour and includes an upper head protecting projection 12, an upper bar 14 extending transversely just above the eyes of the mask wearer, a lower bar 16 positioned somewhat below the eyes and a chin guard 18. Openings designated respectively 13, 15 and 17 are provided over the forehead for the eyes and for the mouth. 45 Side plates designated 19 are adapted to extend beyond the sides of the wearer's face as particularly illustrated in Figure 2. Pairs of apertures 20 are formed in each of the side plates and are longitudinally arranged.

50 The padding utilized to protect the face and head from the shocks of balls hitting the mask is selectively disposed to provide sufficient protection and at the same time allow a substantial ventilating space. The upper pad, designated 21, is adapted to extend across the brow of the mask

wearer and, as illustrated in Figure 3, depends downwardly on the side edges only enough to provide sufficient anchorage. This pad is held in place by means of a cover extension 22 which encircles the bar 14 and is secured to cover flaps 23 and 24, the flap 23 being passed outwardly around the rim of the plate and the flap 24 being passed through the opening 13. Preferably, the extension 22 and the flaps 23 and 24 are secured by a continuous lacing 25. This arrangement provides a three-point engagement which serves to hold the pad 21 very securely in position.

The lower pad 26 is adapted to fit in the area between the wearer's mouth and the point of his chin. Again, the side portions extend upwardly only sufficiently to provide a firm anchorage, having a substantial space between their upper ends and the lower ends of the pad 21. The pad 26 is held in position by cover extensions 27 and 28 which fit in the recess portions 29 in the chin guard and are secured there by the laces 30.

Attention is particularly directed to the harness arrangement provided for holding the mask firmly in position on the head. This arrangement includes the strap 31 which extends around the back of the wearer's head and the interconnecting strap 32 extending over the top of the head. A third strap 33 is passed through an aperture 34 in an upward extension 35 of the upper bar 14 and is secured in position by the buckle 36. This third strap 33 is extended rearwardly over the top of the head and secured to the strap 31. The fastening straps 31 form extensions of the strap 31 and are adapted to be inserted selectively on both sides through either one of the apertures 20—20 and then maintained in position by the buckles 38. The question of which of the two apertures is utilized depends, of course, on the contour of the wearer's head and a high degree of adjustability is thereby provided. While it is only necessary to provide a buckle on one side of the plate, a similar arrangement may be provided, if desired, on the other side. The entire arrangement of the straps forces a pocket-like construction which conforms to the back and sides of the head; holding the mask firmly in position.

The mask is held firmly in position against downward slipping by the strap 33 which serves to maintain the protective extension 12 in the proper position at all times thereby eliminating any possibility of injury to the upper portion of the head by thrown balls or foul tips.

From the above description, it will be appreciated that the mask which is provided has a number of definite advantages. The head protecting extension 12 is of sufficient height to pro-

tect the top of the head from the impact of balls and is securely maintained in position against vertical movement by the strap 33. The air space provided between the upper pad 21 and the lower pad 26 is substantial and permits considerable ventilation as well as improving the visibility. The various adjustment means provided in securing the harness are particularly effective in providing an exact fit.

Having fully described my invention, I claim:

A baseball mask of the bar type comprising an arcuate plate of generally oval outline configuration having a plurality of apertures formed therethrough, the upper portion of said plate when secured in position on a wearer's head extending to a level substantially above the top of the head, and means for securing the plate in position on the wearer's face, said means including side portions on the plate adapted to extend outwardly along the sides of the wearer's face, each of said portions having a plurality of vertically disposed strap receiving apertures formed therein, a first strap adapted for passage through one of said apertures in each side portion, said strap extending laterally around the sides of the wearer's head, a second strap interconnected with said first strap and extending from one side of the head across the top to the opposite side, the points of juncture of said second strap and said first strap being spaced substantially half the distance from said oval plate to the rearmost portion of the first strap, and a third strap secured to the plate at a central point below its upper edge and secured at its other end to the first named strap, whereby the straps collectively form a pocket-like construction holding the mask securely against the wearer's face, the portions of the first strap located forwardly of each of said points of juncture being adapted for angular displacement relative to the portion of said face strap being located rearwardly of said points of juncture when said first strap is shifted from one of the apertures on each side of the face plate to another of the apertures on each side of the face plate.
